UNITED STATES PATENT OFFICE.

HARRY G. GEISSINGER, OF CHICAGO, ILLINOIS, ASSIGNOR TO VAPOR CAR HEATING COMPANY, INC., OF CHICAGO, ILLINOIS, A CORPORATION OF NEW YORK.

HEATING SYSTEM FOR RAILWAY TRAINS.

1,415,872.

Specification of Letters Patent. Patented May 16, 1922.

Application filed May 9, 1919. Serial No. 295,954.

To all whom it may concern:

Be it known that I, HARRY G. GEISSINGER, a citizen of the United States, residing at Chicago, in the county of Cook and State 5 of Illinois, have invented certain new and useful Improvements in Heating Systems for Railway Trains, of which the following is a specification.

My invention relates to the heating of the 10 cars of a railway train provided with an electric circuit, for instance, the circuit of an electrically actuated signaling system which is closed when the train is in operation, or in readiness for operation, for example when the locomotive is coupled up to 15 the cars of the train.

The object of the invention is to provide 20 apparatus for controlling the inflow of steam to the radiators of a car which will be automatically conditioned, when the locomotive is disconnected from a train, to reduce the amount of heating medium passing through the radiators of the car. In this connection I aim to utilize the circumstance that the 25 electric signaling circuit of the train is closed when the car is in service and opened when the car is out of service and thereby effect the desired control of the apparatus by providing the apparatus with an electrically actuated device which will respond 30 to the opening of the said electric signaling circuit to reduce the amount of steam utilized for heating the cars during such periods as the latter are not in service, during which 35 periods it is sufficient to heat the cars only to such temperature as will prevent the freezing of water pipes and fixtures or fittings which may contain water. The steam train pipes of passenger cars, when the cars 40 are not in service, are usually connected to the source of supply of steam in the yard or at the terminal; but in the absence of some special means for reducing the flow of steam to the radiators the cars, when thus standing empty, will be heated to the same temperature at which they are maintained when 45 in service with the train line connected to the locomotive boiler, and the maintenance of temperature at such point during the idle 50 periods is entirely unnecessary and involves a large waste of fuel since railway cars are out of service on the average for a very considerable part of the time, frequently for a longer period on the aggregate than the time 55 which they are in service.

The invention is illustrated, in a diagrammatic manner, in the accompanying drawing which is intended to represent the first car, a part of the second and a part of the locomotive of a railway train provided with an 60 electrically actuated signal system and with a heating system, the operation of which, in accordance with this invention, is conditioned upon whether a circuit through the signaling apparatus is open or closed. 65

Referring to the drawing, 10 designates the outline of a railway car which is provided with a heating coil 11, the inflow of heating medium to which is governed by a valve 12 operated by a magnet or other electrically actuated device 13. In the arrangement shown there are two circuit making and breaking thermostats arranged in the car adapted to act alternately to control the energization of the valve moving device 70 13, these thermostats being set to function at different car temperatures. In the drawing theremostat 14, which may be termed the "high temperature thermostat", functions to maintain the atmosphere of the car 75 at the normal living temperature, say 70° Fahrenheit, while the thermostat 15, termed the "low temperature thermostat", functions to maintain the atmosphere of the car 80 at a much lower temperature but sufficient 85 to prevent freezing of the water pipes, and the like, say at 50° Fahrenheit. 16 is a battery or other local source of supply of electrical energy in the car which is connected with the valve moving device 13, the low 90 temperature thermostat 15 and the high temperature thermostat 14 by wires 17, 18 and 19. This circuit is completed, so as to include either one thermostat or the other, by a wire 20, a switch 21 adapted to bear 95 against either contact 22 or contact 23, a wire 24 connecting contact 22 with a contact 25, with which theremostat 14 cooperates, and a wire 26 connecting contact 23 with contact 27 with which thermostat 15 cooperates. The switch 21 is the armature of an electro-magnet 28 arranged in a circuit comprising wires 29, 30, 31 and 32. This circuit extends through all of the cars of the train, is closed when the locomotive is 100 properly coupled up with the cars of the train, and includes a generator 33, or other source of electrical energy, located at any suitable point on the train, for example, in the locomotive tender, a partial outline of 105 110

which is indicated at 34. The electrical coupling between the car 10 and the adjacent car 35 is shown at 36. A similar coupling 37 is arranged between the car 10 and the locomotive. The circuit just described is part of an electrically actuated signaling system with which the train is provided.

To indicate in a general way the operation of the signaling system I have shown a circuit breaker 38 adapted to cooperate with a contact 39, these elements being interposed between the wires 30, 31 and the circuit breaker being provided with an idler wheel 40 over which passes a signal pull cord 41.

Any suitable type of signalling instrument may be employed. I have shown a signal bell 42 located in a normally open circuit 43 which is closed by a magnetic circuit breaker 44 in series with the generator 33, 45 being a wire connected with conductor 29 and with the circuit breaker 44, 49 a wire leading from the circuit breaker to the generator, and 50 a conductor between the other pole of the generator and wire 32. By pulling down cord 41 the circuit is broken, deenergizing the circuit breaker 44, which thereupon drops its armature 46 upon contact 47 closing the circuit 43 and actuating the signalling device 42. Any suitable means may be employed, automatically operated or otherwise, for opening circuit 43 when the locomotive is disconnected from the train. I have shown for purposes of illustration a circuit breaker 48.

When the locomotive is disconnected from the train the circuit through the electromagnet 28 is broken and switch 21 falls upon contact 23 closing the local circuit from the battery 16 through the low temperature thermostat 15. This thermostat will then control the admission of heating medium to the radiating coil 11 by energizing the magnet 13 so as to attract the armature 12^a to close the valve 12 or by opening the circuit through the magnet 13 to permit the valve 12 to be opened by the fluid pressure in the train line at such intervals as may be necessary to maintain the atmosphere of the car at the desired low temperature, for example, at 50° Fahrenheit. When the locomotive is attached to the train the signaling apparatus will be at once put into condition for operation by putting the coupling 37 in place. As soon as this is done magnet 28 will be energized, due to the closing of its circuit, and will attract its armature 21, breaking the circuit through the low temperature thermostat 15 and closing the circuit from the battery 16 through the high temperature thermostat 14. The heating system of the car is now under the control of a thermostat which functions to maintain the atmosphere of the car at a

normal living temperature, for example, 70° Fahrenheit, as stated.

In the drawing I have shown the high temperature thermostat in control with its contact 25 closed thereby energizing the magnet coil 13 to hold the valve 12 in its closed position. When the temperature of the car falls below the temperature which the high temperature thermostat is set to maintain, this thermostat will move away from its contact 25 and deenergize the valve magnet 13 so as to permit the pressure in the train line to open the valve 12. When the low temperature thermostat 14 is in control the operation is the same as above described with the exception that the contact 25 remains open so the rise and fall of the car temperature effects the opening and closing of the local circuit at the low temperature contact 27. These particular arrangements are not at all essential and are shown purely for the purpose of illustrating one practical embodiment of the invention. In fact, so far as details of construction and arrangement are concerned, apparatus as shown might be modified to a very considerable extent without departing from the principle of my invention as defined in the claims appended hereto.

I claim:

1. In combination with a railway car and an electrically actuated apparatus, the circuit of which is closed through a source of supply of current when the car is coupled up in a train for service and opened when the car is uncoupled from the train, a heating element in the car, and means conditioned by the actuation of said apparatus to maintain the atmosphere of the car at one of a plurality of selected temperatures whereby the amount of heating medium introduced into the heating element is made to depend upon whether said electric circuit is closed or open.

2. In combination with a railway car and an electrically actuated apparatus, the circuit of which is closed through a source of supply of current when the car is coupled up in a train for service, a heating element in the car, and means conditioned by the actuation of said apparatus for selectively controlling the operation of said heating element whereby the atmosphere of the car is maintained at different selected temperatures dependent upon whether said electric circuit is open or closed.

3. In combination with a railway car and an electrically actuated apparatus, the circuit of which is closed through a source of supply of current when the car is coupled up in a train for service, a heating element in the car, and thermostatic means selectively conditioned when said electric circuit is closed to maintain the atmosphere of the car at a relatively high temperature and

when said circuit is open to maintain the same at a lower temperature.

4. In combination with a railway car and an electrically actuated apparatus, the circuit of which is closed through a source of supply of current when the car is coupled up in a train for service and opened when the car is disconnected from the train, a heating element in the car, a source of supply 10 of heating medium, a valve to control the flow of heating medium from said source of supply to the heating element, and a pair of thermostats in the car set to function at different temperatures one of which is 15 adapted to control the movements of the valve when said electric circuit is open and the other when said circuit is closed.

5. In combination with a railway car and an electrically actuated apparatus, the circuit of which is closed through a source of supply of current when the car is coupled up in a train for service, a heating element 20 in the car, a source of supply of heating medium, a valve to control the flow of heating medium from said source of supply to 25

the heating element, high temperature and low temperature circuit making and breaking thermostats, electrically actuated mechanism for effecting the movements of said valve adapted to be controlled by said thermostats alternately, said electrically actuated apparatus in said first mentioned circuit being adapted, when energized, to close a circuit through one of said thermostats and the valve moving mechanism, and when 30 de-energized to close a circuit through the other thermostat and said valve moving mechanism.

6. In combination with a railway car, signalling apparatus comprising an electric 40 circuit, means for closing said circuit upon coupling up of the car in a train and breaking this circuit on uncoupling of the car, a heating apparatus in the car and means for controlling the supply of heating medium 45 to said heating apparatus the operation of which means is dependent upon whether said electric circuit is open or closed.

HARRY G. GEISSINGER.
